UNITED STATES PATENT OFFICE.

JOHN HAWLEY TAUSSIG, OF PHILADELPHIA, PENNSYLVANIA, ASSIGNOR TO THE UNITED GAS IMPROVEMENT COMPANY, OF PHILADELPHIA, PENNSYLVANIA, A CORPORATION OF PENNSYLVANIA.

CLAMP FOR VERTICAL-GAS-RETORT DOORS.

1,105,582.

Specification of Letters Patent. Patented July 28, 1914.

Application filed January 20, 1913. Serial No. 743,026.

To all whom it may concern:

Be it known that I, JOHN HAWLEY TAUSSIG, a citizen of the United States, residing at the city of Philadelphia, in the county of Philadelphia and State of Pennsylvania, have invented a certain new and useful Clamp for Vertical-Gas-Retort Doors, of which the following is a specification.

The cotter-bars or other hinged devices by which the bottom or discharge doors of vertical gas retorts are seated and closed, are exposed to conditions which cause them to twist, warp, bend or otherwise get out of position or place.

The principal object of the present invention is to provide a compact, efficient and reliable clamp or clamping device which shall have a sufficiently wide range of operation to insure proper engagement with the cotter-bar or like device and which shall serve to expeditiously and properly seal and tightly close the door.

Another object of the invention is to provide a clamp for the purpose described which will rapidly seat the door and comparatively slowly clamp it or force it to its seat.

Other objects of the invention will appear from the following description which will be made in connection with the embodiments of it selected from other embodiments for illustration in the accompanying drawings, in which—

Figure 1, is a plan view, partly in section, of the underside of a door showing in application thereto a clamp embodying features of the invention. Fig. 2, is a sectional view taken on the line 2—2 of Fig. 1. Fig. 3, is an end view of the clamp. Figs. 4 and 5 are sectional views taken on the lines 4—4 and 5—5 of Fig. 3, and Figs. 6 to 8, are diagrammatic views illustrating a modification and in which the parts are turned out of their proper planes for the sake of clearness in description.

In the drawings 1 is a cotter-bar or door carrier hinged in respect to the shaft 2, which is provided with a lug or projection 3, by means of which the cotter-bar is turned up into closing position.

4, is the bottom or discharge door carried by the cotter-bar through the intervention of an eccentric connection 5 operated by a handle 6.

7, is the door frame. Certain off-takes 8

and 9 are shown in respectively the door and frame.

The parts described so far as they may be new and patentable alone or in combination are not claimed herein, since they form the subject-matter of my applications serially numbered 743,025 and 743,027, filed Jan'y 20, 1913.

10 and 11 are duplicate cantilevers or floating levers and they are connected together by a link 12, which may be swung in and out under and lift and drop the free end of the cotter-bar 1. Inasmuch as the levers 10 and 11 and their connections are duplicates, a description of but one will be given as the other is just like it.

13 is a shaft mounted in bearings 14 carried for example by a portion of the door frame and provided with a handle 15. Fast on this shaft is an eccentric 16 and also a two-part eccentric 17. The strap 18 of the eccentric 16 is connected with the free end of the lever 10 and the forked strap 19 of the two parts of the eccentric 17 is connected with the lever 10 intermediate of its ends. The eccentrics 16 and 17 are set at proper angular distances apart. On the shaft 13 there is a fast collar 20 provided with lugs 21 that contact or collide with lugs 22 on the eccentric straps 19. Fixed as to the door frame is a stop 23 with which a projection 28 on the eccentric strap 19 may collide.

In use the handle 15 is turned and the lugs 21 and 22 collide and the eccentrics are turned so as to drop their straps. The result of this is that the link 12 is dropped or moved away from the shaft 13 and the clamp, as a whole, is swung out toward the right in Fig. 2 so as to clear and release the end of the cotter-bar. This position corresponds to the opening of the door 4. The purpose of the stop 23 is to insure turning of the eccentrics in their straps. In closing the door the cotter-bar is brought up into elevated position and as has been said this position may vary considerably but the reach of the clamp is sufficiently great for it to get in under the cotter-bar without fail. The handle 15 is turned so as to let the clamp, or more accurately, the link 12 swing in under the cotter-bar and the turning of the handle 15 and shaft 13 operates the eccentrics and causes them one to push down the strap 18 and the other to pull up the strap 19 with

the result that the cotter-bar is lifted so as to seat and tightly close the door.

In the modification shown in Figs. 6 to 8, the construction and operation is the same, except that the eccentric 16^a is somewhat peculiarly shaped in order to give a quick lift and a slow final clamping movement. As indicated in Fig. 6, 24 and 25 indicate position and in Fig. 6 the parts are shown 10 in unclamped position. The eccentric 16^a is struck from two centers and it therefore has a quick throw. The cams 26 and 27 attached respectively to the eccentric and strap and arranged in a plane parallel to them serve 15 to hold the parts in the position shown in Fig. 6 in case by reason of weight, the eccentric strap should tend to drop. When shifted 13^a is turned through 90° the parts are in the position shown in Fig. 7 and the 20 eccentric 16^a has pushed its strap to the limit of its downward movement, while the eccentric 17^a has caused comparatively little change in the position of its strap. As a result of this the lever 12^a has been quickly 25 lifted up into the position 24, thus the door is quickly lifted up to its seat. During the next 90° of revolution of the shaft 13^a the eccentric or cam 16^a produces no movement of its strap since its operative surface is 30 concentric with the shaft 13^a, but the eccentric 17^a has lifted the link 12^a from the position 24 to the position 25 slowly and the distance between 24 and 25 is short, so that the pressure necessary for tightening the 35 door is applied slowly and therefore advantageously.

It will be obvious to those skilled in the art that modifications may be made in details of construction and arrangement and 40 hence the invention is not limited as to those matters, nor do I desire to limit my invention further than the state of the prior art may require.

What I claim is:

45 1. A clamp for vertical gas retort doors comprising the combination of a rotatable operating shaft, a pair of cantalivers having their free ends adapted to operate on a part of the door, a pair of eccentrics on said 50 shaft provided with straps connected to one

of said levers, and a lug on the shaft for turning the straps and levers, substantially as described.

2. A clamp for vertical gas retort doors comprising the combination of a rotatable 55 operating shaft, a pair of cantalivers having their free ends adapted to operate on a part of the door, a pair of eccentrics on said shaft provided with straps connected to one of said levers, a lug on the shaft for turning 60 the straps and levers, and a fixed back stop for the straps and levers, substantially as described.

3. A clamp for vertical gas retort doors comprising the combination of a rotatable 65 operating shaft, a pair of cantalivers, a link connecting the free ends of the cantalivers, a pair of eccentrics on said shaft provided with straps connected to one of said levers, and a lug on the shaft for turning the straps 70 and levers, substantially as described.

4. A clamp for vertical gas retort doors comprising the combination of a cantaliver, an operating shaft, an eccentric on said shaft having a strap connected with the lever, 75 and an eccentric on the shaft struck from two centers and provided with a strap for effecting a quick lift, substantially as described.

5. A clamp for vertical gas retort doors 80 comprising the combination of an operating shaft, a cantaliver, an eccentric and strap connecting the lever and shaft, a second eccentric struck from two centers and arranged on the shaft and provided with a 85 strap connected with the lever, and cams applied to the faces of the second eccentric and its strap, substantially as described.

6. In a clamp for vertical gas retort doors, the combination of a cantaliver pivoted at 90 two points and having its free end adapted to operate upon a part of the door, and an eccentric for shifting one of the pivot points, substantially as described.

In testimony whereof I have hereunto 95 signed my name.

JOHN HAWLEY TAUSSIG.
